(57) **CLAIM**

The ornamental design for an exhaust fan, as shown and described.

DESCRIPTION

FIG. 1 is a first perspective view of an exhaust fan showing a new design;

FIG. 2 is another perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken lines in the drawings illustrate the portions of the exhaust fan, which form no part of the claimed design.
